DRY SHAVING APPARATUS

Guillaume Barsch, Geneva, Switzerland

Application March 18, 1948, Serial No. 15,673
In Switzerland June 17, 1947

8 Claims. (Cl. 30—34)

1

The present invention relates to a dry shaving apparatus, including at least one cutting member and at least one abrading member mounted on a body rotating within a sheath provided with openings, comprising means allowing the removal and the positioning of the cutting and abrading members rapidly and without fumbling. In a preferred embodiment, the said body is provided with a central part driven by a driving shaft and comprising at its ends cheeks which receive the ends of the above-mentioned members, one of these cheeks being provided with openings within each of which is engaged a lug extending from one of the ends of each of these members, whereas the other cheek comprises radial slots into each of which is engaged a lug provided at the opposite end of each of these members, a holding member being mounted around at least one part of the said slotted cheek to hold radially these lugs in working position, this holding member having an opening capable of coinciding in succession with the various slots, when it is made to rotate around the cheek which it carries, in order then to allow free passage for the corresponding lug and thus permit, with ease and without fumbling, the positioning and removal of the above-mentioned members.

The accompanying drawing shows, by way of example, an embodiment of the dry shaving apparatus according to the invention.

Fig. 1 is an elevation view of the rotating body included in the apparatus, the sheath surrounding this body being removed.

Fig. 2 is a plan view corresponding to Fig. 1.

Fig. 3 is a longitudinal sectional view according to III—III of Fig. 2.

Fig. 4 is a cross sectional view according to IV—IV of Fig. 3, it being understood that certain members are removed.

Fig. 5 shows a detail in elevation.

Fig. 6 is a view from below corresponding to Fig. 5.

Fig. 7 is an outer view, in elevation, of the head of the apparatus showing the sheath.

Fig. 8 is a plan view corresponding to Fig. 7, partially in section.

Fig. 9 is a detail view in vertical section.

Fig. 10 is a perspective detail view.

Fig. 11 is an elevational view on the opposite side to that according to which the apparatus is viewed in Fig. 7.

The dry shaving apparatus shown in the drawing includes a rotating body formed of a cylindrical portion 1 and two cheeks 2, 3 fixed to a shaft 4 driven by a motor not shown. This body

rotates within a sheath 5, of cylindrical shape, secured by bayonet joint, as shown at 6, to the base 7 of the shaving apparatus.

On the rotating body 1, 2, 3 are mounted two main cutting members 8, two auxiliary cutting members 9 and two abrading members 10. The members of each of these pairs are placed in diametrically opposed positions and are angularly spaced at 60° with respect to each other. (See Fig. 2.) These cutting and abrading members are arranged to act alternately on the surface to be shaved when the sheath 5, which is provided with openings as shown in Fig. 7, is applied against this surface. The cutting members then shear the hairs extending through these openings, and the abrading members sort of grind down the remaining part of the hairs thus cut, so as to shave very closely the part of the skin extending slightly inside each of the openings 20 in the sheath 5.

The cheek 2 is provided with six openings 11 each of which is designed to receive a lug 12 extending from one of the ends of each of the members 8, 9 and 10. The other cheek, 3, has six radial slots 13, into each one of which extends a lug 14 provided at the opposite end of each of the members 8, 9 and 10. A holding member 15, cup-shaped, is mounted around one part of the said slotted cheek 3. The cylindrical part of this holding member 15 has a radial slot 16 which, when the member 15 is made to rotate by hand around the cheek 3, may be brought successively in registry with each of the slots 13. When the slot 16 occupies an intermediate position between the two slots 13, the cylindrical part of the member 13 radially holds the lugs 14 which bear against it under the action of the centrifugal force due to the rotation of the rotating body 1, 2, 3. This holding member 15 thus holds the lugs 14 in working position. When, on the other hand, the slot 16 coincides with any one of the slots 13, the lug 14 may easily be freed from the corresponding slot 13, by pulling radially outwards the corresponding end of the member to which it belongs. Once the lug 14 has been freed from the cheek 3, the lug 12 may be withdrawn at ease from the corresponding opening 11 of the cheek 2. Thus, each of the members 8, 9, 10 may easily be removed or placed in position through a very simple operation.

The bottom of the cup, formed by the member 15, is interiorly provided with a series of swellings 17, spaced at 30° from each other and obtained by embossing the metal of this bottom. These swellings, twelve in number, are arranged to co-

operate with twelve notches 18 of a cylindrical part belonging to the cheek 3. A flexible metallic ring 19 is interposed between the outer surface of the bottom of the member 15 and the conical end portion 20 of the central part 1, to urge continual cooperation of the parts 17 and 18. It will readily be understood that, when the projecting parts 17 are each engaged in one of the notches 18, the member 15 will be stable and be prevented from accidental rotation about the cheek 3. On the other hand, through hand operation of the milled outer surface 21 of the member 15, this latter may be made to rotate with respect to the cheek 3 so as to bring it into any desired angular position with respect to this cheek.

The abrading members shown in the drawing are each formed by an abrasive stone 10, a part of which is of general cylindrical shape 22, provided with oblique slots 23. The main cutting members 8 are formed of metallic blades whose cutting portion 24 comprises a series of slanting edges, as shown more clearly in Fig. 1. The cutting portion 24 moves practically in contact with the inner surface of the perforated sheath 5. This sheath, in the perforated part applied to the surface to be shaved, is of very small thickness, for example of the order of $5/100$ mm. The cylindrical surface 22 of the abrading members 10 rotates at a short distance from the inner surface of the sheath 5, but without contacting the same. The auxiliary cutting members 9 are formed as follows; as in the case of the members 8, they comprise a metallic blade each arranged on the rotating body along a radial plane with respect to the axis of this body, but instead of being provided with a cutting part all along one of their longer sides, the active part of the members 9 is composed of two cutting parts 25, 26 merely at right angles to each other (Figs. 3 and 9) and rotating within the sheath 5, one opposite one of the ends of its cylindrical part, and the other opposite the adjacent end part 27, plane-shaped, of this sheath.

In this region of the sheath, the openings are formed by slots 28. These slots are obliquely arranged with respect to the axis of the rotating body and extend along the common circular edge 29 of the adjacent regions, respectively cylindrical and plane, of this sheath. The reason for such an arrangement is to permit of close shaving, in places where little room is available, by applying the edge 29 to the region to be shaved.

According to Fig. 10, there is shown a modification of the slots 28 which are radial instead of being oblique. The space remaining between adjacent slots constitutes a kind of tooth and, as shown in Fig. 10, every other tooth discloses a cross slot 30.

A spring 39 holds the cutting part 26 of the members 9 in the working position, in contact with the bottom surface 27.

The part of the sheath 5, which is applied to the surface to be shaved, is provided with a series of small holes 31, as shown in Fig. 7. On both sides of the area of small holes 31 are two areas of slightly larger holes 32; and in the part diametrically opposite to the area of holes 31, there is provided, in the sheath 5, large sized holes 33, designed for the automatic removal of the cut hairs under the action of rotation of the rotating body 1, 2, 3. A lid 34, pivoting at 35 on the sheath 5, embraces half the periphery of this body, in order to hide the large holes 33. For cleaning purposes, it is merely necessary to separate the

part 34 from the sheath 5, by making it pivot at 35. The cut hairs which are then deposited on the inner surface of 34, may thus easily be removed, by simple blowing or with a small brush.

5 What I claim is:

1. In a dry shaving apparatus including a cylindrical sheath, a body rotating inside the sheath, and at least one cutting and one abrading member mounted on the body, the sheath having openings therein before which the cutting and abrading members pass alternately, the improvement which consists in the body comprising a central portion having a drive shaft extending axially therefrom, and a pair of end cheeks rigidly connected to the central portion, one cheek having holes and the other radial slots therein, the cutting and abrading members having lugs at both ends for engaging respectively in the holes of one cheek and the slots of the other, and a holding member rotatably mounted on the slotted cheek and having an aperture therein registering in turn with each of the slots thereby to permit disengagement of each lug from the enveloping slot as the aperture of the holding member is presented to each slot in turn.

2. An apparatus according to claim 1 wherein the slotted cheek and holding member are provided with complementary notches and bosses, the holding member being slightly axially slideable to permit disengagement of the bosses from the notches, and spring means yieldably retaining the bosses in the notches, the bosses and notches being so disposed that the holding member is held in holding and disengaging position of the lugs against accidental displacement therefrom.

3. An apparatus according to claim 1 wherein each cutting member comprises a blade located in a radial plane of the body.

4. An apparatus according to claim 3 wherein the cutting edge of the blade, when the body rotates, is almost in contact with the inner surface of the sheath at the point thereof where the openings are provided, thereby to shear almost all that part of the bristles penetrating through the openings.

5. An apparatus according to claim 1 wherein the each abrading member comprises a stone having an abrading surface arranged to rotate past the inner surface of the sheath at the point thereof where the openings are provided.

6. An apparatus according to claim 5 wherein the abrading surface of the stone, when the body rotates, is almost in contact with the inner surface of the sheath.

7. An apparatus according to claim 1 wherein at least one cutting member comprises a blade having two cutting edges substantially at right angles to one another, one edge rotating in a plane parallel and closely adjacent to a plane end of the sheath and the other opposite the cylindrical end portion thereof, the plane end and cylindrical end portion of the sheath being provided with slots each extending on both sides of the circular edge common to said end and portion.

8. An apparatus according to claim 1 wherein a portion of the cylindrical sheath is provided with a series of relatively large apertures to permit automatic removal of cut and abraded bristles, and a removal lid covering said apertures.

GUILLAUME BARSCH.
